GUARD RAIL CONNECTER

Filed Oct. 20, 1927

2 Sheets-Sheet 2

Fig. 3.

A technical drawing of a fastener assembly. The assembly includes a base 33, a central vertical member 31, and a top cap 10. The top cap 10 has a central slot 35. A fastener 34 is secured through the top cap 10 and the central vertical member 31 into the base 33. The base 33 is shown in cross-section, revealing internal features labeled 36 and 37. A side view of the base 33 shows a rib 38. Reference numerals 11 and 32 are also present, likely referring to other parts of the assembly or related components.

UNITED STATES PATENT OFFICE.

HARRISON R. AKERS, OF TYLER, TEXAS.

GUARD-RAIL CONNECTER.

Application filed October 20, 1927. Serial No. 227,585.

This invention relates to guard rail connectors and more particularly to the provision of clamps and spacing elements or filler blocks for maintaining the guard rail 5 in properly spaced relation to a track rail.

An important object of the invention is to provide a device of this character which may be readily adjusted without dismantling the guard rail and without the necessity of bending either the guard or track rails to permit such adjustment.

A further object of the invention is to provide a structure such that the adjustment may be rapidly effected and, at the same 15 time, an extremely secure connection between the rails provided.

A still further object of the invention is to produce a device of this character which will be durable in service and a general improvement in the art.

These and other objects I attain by the construction shown in the accompanying drawings, wherein for the purpose of illustration is shown a preferred embodiment of 25 my invention and wherein:

Figure 1 is a plan view partially broken away of a guard rail attached by connectors constructed in accordance with my invention;

Figure 2 is a side elevation thereof partially broken away;

Figure 3 is a section on the line 3—3 of Figure 1;

Figure 4 is a section on the line 4—4 of Figure 1;

Figure 5 is a section on the line 5—5 of Figure 3.

Referring now more particularly to the drawings, the numeral 10 generally designates a track rail and 11 a guard rail having its central portions paralleling and its end portions oppositely diverging from the track rails. As is well known to those familiar with the art, it is necessary that 40 these guard rails must be held in a predetermined spaced relation to the track rail. This I accomplish by providing at the center of the guard rail a clamping mechanism whereby the guard and track rails are connected holding said central portions in properly spaced relation and providing at the divergent end portions of the guard rail spacer blocks accomplishing the same function.

The clamping mechanism at the center of 55 the guard rail comprises a U-shaped clamp

12 adapted to extend beneath the bases of the track rail 10 and guard rail 11 and having the arms 13 and 14 thereof relatively heavy and provided upon the inner faces adjacent their lower ends with recesses 15. 60 The arm 13 has its inner face 16 at an acute angle to the transverse axis of the clamp, while the inner face 17 of the arm 14 is arcuately curved. Coacting with the arm 13 and with the flange of the track rail 10 is a wedge 18 having its inner face constructed to fit against the rail web between the head and base thereof and its outer face constructed for coaction with the inclined face 16 of the arm 13. At the butt or thicker end 70 of the wedge 18, this outer face has projecting therefrom a lug 19 apertured for the passage of a bolt 20 and the head of this bolt has engagement with the outer face of the wedge 18, preventing rotation thereof, as 75 indicated at 21. The arm 13 has an aperture through which the bolt may pass and between the nut and the arm, a relatively heavy spring lock washer 22 is disposed. This lock washer tends both to prevent rotation 80 of the nut and to provide a longitudinal take-up on the bolt, causing relative shifting of the clamp 12 and wedge 18 in event any looseness occurs in the connection.

Upon the outer face of the wedge at the 85 lower edge thereof, an outstanding flange 23 is formed which is adapted to enter the recess 15 and prevent dropping of the clamp in event of excessive looseness. Associated with the arm 14 is a pivot block 24 having its inner face constructed to fit against the inner face of the guard rail and its outer face provided with a vertical arcuately curved groove 25 adapted to fit against the curved face 17 of the arm 14. 90

It will be obvious that this face will act as a pivot about which the guard rail may rock, if in taking up the slack in the connections one end of the guard rail is moved outwardly a greater distance than the opposite end. Between the rails is disposed a filler block formed in two sections comprising complementary wedges 26 and 27, the inclined faces of which confront and are provided one with a groove 28 and the other with a tongue 29 to fit this groove. At the smaller end of the tongue bearing wedge, a series of longitudinally spaced openings 30 is formed for the passage of a retaining pin which will abut the base end of the other of 100 105 110

the wedges and prevent relative shifting of the wedges in a direction such that the distance between their outer faces would be decreased. These outer faces are constructed to fit against the adjacent faces of the guard rail and track rail.

The filler block mechanisms between the ends of the guard rail and track rail each comprises a pair of wedge elements 31 and 32 so constructed that when in engagement with one another, their outer faces 33 and 34 are disposed at an angle to one another equal to the angle between the angular end portions of the guard rail and the track rail. These outer faces are constructed to fit against the flanges of the track and guard rails and the inner faces of the wedge elements are provided one with a groove 35 and the other with a tongue 36 for coaction with this groove. One of these wedges has formed therethrough a series of openings 36, while the other of the wedges has formed therethrough a single opening 37. A bolt 38 passing through one of the openings 36, the opening 37 and openings formed in the webs of the track and guard rails maintains the wedges 31 and 32 in properly adjusted positions and prevents any accidental displacement thereof. In this connection, it is pointed out that the tongue and groove connection provided upon the wedge elements in each connection prevents vertical disalignment of these sections and assures proper positioning thereof.

In event any looseness occurs in the connection between the track and guard rails, this may be taken up by removing the bolts 38 and driving up on the wedge elements 31 until the next bolt hole 36 is aligned with the bolt opening 37. The central filler block is then similarly taken up by removing the pin which has been inserted in the opening 30 and then driving the block 27 longitudinally until the next opening extends beyond the block 26, so that the pin may be inserted therethrough. It is pointed out that the constructions employed in the filler blocks are such that there is no interference with relative longitudinal movement of the wedge elements other than the friction. Adjustment may also be made in connection with the clamp by tightening the nut of the bolt 21. The under surface of the filler block section 26 is preferably provided with depending lugs 26a which engage opposite side faces of the clamp 12, so that this section is held against longitudinal displacement with relation to the rail 10. Any other suitable means for preventing this displacement may be employed.

Since the construction hereinbefore set forth is capable of a certain range of change and modification without materially departing from the spirit of the invention, I do

not limit myself to such specific structure except as hereinafter claimed.

I claim:

1. In combination, a track rail and a guard rail, a clamp connecting the track and guard rails at the center thereof and having engagement with the outer face of the guard rail permitting oscillation of the ends of the guard rail toward and away from the track rail, spreader blocks between the rails at the centers thereof and spreader blocks between the rails at the ends thereof.

2. In combination, a track rail and a guard rail, a clamp connecting the track and guard rails at the center thereof and having engagement with the outer face of the guard rail permitting oscillation of the ends of the guard rail toward and away from the track rail, spreader blocks between the rails at the centers thereof, spreader blocks between the rails at the ends thereof, each of said spreader blocks being formed in two sections having wedging engagement with one another and having smooth confronting faces and means for securing the sections in adjusted position with relation to one another.

3. In combination, a track rail and a guard rail, a clamp connecting the track and guard rails at the center thereof and having engagement with the outer face of the guard rail permitting oscillation of the ends of the guard rail toward and away from the track rail, spreader blocks between the rails at the centers thereof, spreader blocks between the rails at the ends thereof and adjustable means upon said clamp for regulating the distance between the track and guard rails.

4. In combination with track and guard rails, a clamp engaging the rails at the center of the guard rail, said clamp being substantially U-shaped and opposing the outer face of each rail, a pivot block abutting the outer face of the guard rail and with which the arm of the clamp pivotally engages, a wedge abutting the outer face of the track rail and engaged with the opposed arm of the clamp and filler blocks between the rails at the center and ends thereof, said filler blocks each being formed in adjustably engaging sections to regulate the distance between the rails.

5. In combination with track and guard rails, a clamp engaging the rails at the center of the guard rail, said clamp being substantially U-shaped and opposing the outer face of each rail, a pivot block abutting the outer face of the guard rail and with which the arm of the clamp pivotally engages, a wedge abutting the outer face of the track rail and engaged with the opposed arm of the clamp and filler blocks between the rails at the center and ends thereof, said filler blocks each being formed in adjustably engaging

sections to regulate the distance between the rails, said sections having smooth confronting faces.

6. In combination with track and guard rails, a clamp engaging the rails at the center of the guard rail, said clamp being substantially U-shaped and opposing the outer face of each rail, a pivot block abutting the outer face of the guard rail and with which the arm of the clamp pivotally engages, a wedge abutting the outer face of the track rail and engaged with the opposed arm of the clamp, filler blocks between the rails at the center and ends thereof, said filler blocks each being formed in adjustably engaging sections to regulate the distance between the rails, one of the sections of each of said filler blocks having a longitudinally spaced series of openings for the passage of an element preventing movement of the sections in a direction decreasing the width of the filler blocks.

10 15 20

7. In combination with track and guard rails, a clamp engaging the rails at the center of the guard rail, said clamp being substantially U-shaped and opposing the outer face of each rail, a pivot block abutting the outer face of the guard rail and with which the arm of the clamp pivotally engages, a wedge abutting the outer face of the track rail and engaged with the opposed arm of the clamp, filler blocks between the rails at the center and ends thereof, said filler blocks each being formed in adjustably engaging sections to regulate the distance between the rails, a lug upon the butt end of the wedge, a bolt passing through said lug and the associated arm of the clamp and means arranged between the arm of the clamp and the nut of the bolt urging the bolt longitudinally and retaining the nut against rotation thereon.

25 30

8. In combination with track and guard rails, a clamp engaging the rails at the center of the guard rail, said clamp being substantially U-shaped and opposing the outer face of each rail, a pivot block abutting the outer face of the guard rail and with which the arm of the clamp pivotally engages, a wedge abutting the outer face of the track rail and engaged with the opposed arm of the clamp, filler blocks between the rails at the center and ends thereof, said filler blocks each being formed in adjustably engaging sections to regulate the distance between the rails, and lugs upon one of said blocks holding said block against movement with relation to the clamp in a direction transverse to the clamp.

35 40 45 50 55 60

In testimony whereof I hereunto affix my signature.

HARRISON R. AKERS.
